(57) **CLAIM**

The ornamental design for a gas tank, as shown and described.

DESCRIPTION

FIG. 1 is a perspective view of a gas tank according to the present disclosure;

FIG. 2 is a front view of the gas tank of FIG. 1;

FIG. 3 is a rear view of the gas tank of FIG. 1;

FIG. 4 is a left side view of the gas tank of FIG. 1;

FIG. 5 is a right side view of the gas tank of FIG. 1;

FIG. 6 is a top view of the gas tank of FIG. 1; and,

FIG. 7 is a bottom view of the gas tank of FIG. 1.

The broken lines immediately adjacent the shaded areas represent the bounds of the claimed design while all other broken lines are directed to environment and are for illustrative purposes only; the broken lines form no part of the claimed design.
